J. JANUCHOWSKY,
CLOSURE FOR BARRELS,
APPLICATION FILED NOV. 6, 1914.

1,242,352.

Patented Oct. 9, 1917.

UNITED STATES PATENT OFFICE.

JOHN JANUCHOWSKY, OF ST. LOUIS, MISSOURI.

CLOSURE FOR BARRELS.

1,242,352.

Specification of Letters Patent.

Patented Oct. 9, 1917.

Application filed November 6, 1914. Serial No. 870,575.

To all whom it may concern:

Be it known that I, JOHN JANUCHOWSKY, a citizen of the United States of America, and a resident of the city of St. Louis and 5 State of Missouri, have invented certain new and useful Improvements in Closures for Barrels, of which the following is a specification.

The primary object of this invention is 10 to provide an improved closure for barrels whereby the closure when removed is suspended from the barrel so it cannot become misplaced or lost.

Another object is to provide an improved 15 closure with improved securing means whereby the closure is firmly braced against outward pressure from the contents of the barrel.

Other and further objects will appear in 20 the specification and be specifically pointed out in the appended claims, reference being had to the accompanying drawings exemplifying the invention, and in which,

Figure 1 is a plan view of a barrel with 25 a closure showing this improved securing device attached thereto.

Fig. 2 is a vertical section of the upper portion of a barrel taken on the line II—II, Fig. 1.

Fig. 3 is a sectional view, similar to Fig. 2, but showing the closure in the position of being removed.

Fig. 4 is an enlarged fragmentary section taken on the line IV—IV, Fig. 1.

Referring to the drawings: 1 designates 35 a barrel which has a removable closure 2. Secured to the top of said closure are a pair of retaining strips 3 which are adapted to retain a straight-way portion 4 of the swingingly mounted member 5, said member 5 having right angled bent portions 6. The ends of said bent portions 6 are pivotally secured to the side wall of the barrel 1 as shown at 7. The straight-way portion 4 of 40 the swingingly mounted member 5 is mounted at each end in the recesses 8 which are formed in the under side of the strips 3.

Secured to one side of the barrel 1 is a supporting bracket 9, said bracket having a 50 bent portion 10 which is adapted to be engaged on the top edge of the barrel. The outside portion 11 of said bracket is adapted to be engaged beneath the upper barrel hoop 12 and secured thereto. Secured to the top 55 side of the closure 2, diametrically opposite

to the engaging position of the bracket 9, is a locking member 13 having a sliding bolt 14. Said bolt is adapted to engage an opening 15 which is formed in the side wall of the barrel 1.

With this improved form of closure for barrels, which is more especially adapted to be used on barrels for shipment, the same closure can be used over and over without any deterioration thereof except ordinary wear. 65 Ordinarily barrel heads are broken in order to unpack the barrel. As shown in Figs. 1 and 2, the closure 2 is securely fastened to the barrel. When it is desired to remove said closure, the sliding bolt 14 of 70 the locking member 13 is disengaged from the opening 15, and the portion of the closure 2 to which the locking member is secured is lifted and drawn forward, see Fig. 3, the retaining strips 3 being allowed to 75 slide over the straight-way portion 4 of the swinging member 5. When the edge of the closure 2 has been disengaged from the bracket 9, the closure is swung upward and turned over as shown by dotted lines A in 80 Fig. 3.

In replacing the closure on the barrel, the portion B of the closure is engaged in the bracket 9, and the closure is depressed 85 in position so that the locking member 14 will be in position of alinement with the opening 15. Then the locking member is engaged in said opening.

Attention is called to the position of the swingingly mounted member 5 which rests 90 on the top of the closure 2 when the closure is secured to the barrel, the right-angled portions 6 and straight-way portion 4 of the swingingly mounted member 5 engaging the top surface of the closure. As the ends of 95 the portions 6 are pivoted to the barrel 1, as shown at 7, the closure is very firmly braced against any end pressure of the contents of the barrel, as no swinging movement can be given to the member 5 until the closure has been disengaged from the bracket 9, which can only be after the closure has been unbolted and the closure moved to the position shown in Fig. 3.

In providing an improved locking member for a closure so the locked position of the sliding bolt 14 can be sealed, the locking member 13 has a base plate 16 which is secured to the top side of the closure 2. 105 From this base plate an upwardly bent por- 110

tion 17 and a struck-out portion 18 are formed which serve as bearings to the sliding bolt 14. In alinement with the portion 18 is formed an upwardly bent portion 19 which serves as a rear stop to the bolt. The bolt 14 has a right-angled bent portion 20, the end of which is bent rearwardly as shown at 21. This portion 21 of the bolt 14 is adapted to engage an upwardly formed portion 22 of the base plate, there being an opening 23 formed in said portion 22 which is adapted to aline with the opening 24 that is formed in the portion 21 of the sliding bolt when said bolt is in locked position. The seal wire 25 is then inserted in the openings 23 and 24, and the seal 26 is secured to the ends of the seal wire.

What I claim is:

1. The combination of a barrel, a closure, and a swingingly mounted member, said member having angular bent portions formed thereon, guideways located in the top of said closure, said member being mounted at one end in said guideways, and swingingly mounted at its opposite end to said barrel, said angular bent portions of said member adapted to bear against the top of said closure.

2. The combination of a barrel, a closure, and a swingingly mounted member, guideways located in the top of said closure, said member being mounted at one end in said guideways and mounted at its opposite end to said barrel above said closure, said member adapted to brace said closure against outward pressure when said closure is mounted in one end of said barrel.

3. The combination of a barrel, a closure, and a swingingly mounted member, guideways located on the top of said closure, a bifurcated bracket secured to the inside wall of said barrel, a locking member secured to said closure, said swingingly mounted member being mounted at one end in said guideways and mounted at its opposite end to said barrel above said closure, said swingingly mounted member adapted to brace said closure against outward pressure when said closure is mounted in said

bracket, and secured to said barrel by said locking member.

4. The combination of a barrel, a closure, and a swingingly mounted member, guideways located on the top of said closure, a bifurcated bracket secured to the inside wall of said barrel, a locking member secured to said closure, said swingingly mounted member being mounted at one end in said guideways and mounted at its opposite end to said barrel above said closure, said swingingly mounted member adapted to brace said closure against outward pressure when said closure is mounted in said bracket and secured to said barrel by said locking member, said guideways providing means for allowing said closure to become disengaged from said bracket.

5. The combination of a barrel, a closure, and a swingingly mounted member, a pair of guideways formed in the top of said closure, said member comprising a straight-way portion and a pair of right-angled bent portions, said straight-way portion of said member being secured in said guideways, the ends of said right angled portions being pivotally mounted to the wall of said barrel above said closure, a bifurcated bracket secured to the inside wall of said barrel, said closure adapted to engage said bracket, said guideways forming means for allowing said closure to engage and disengage said bracket.

6. In a barrel, a closure, a bifurcated bracket secured to the inside wall of said barrel, a swinging member pivotally mounted at one end to said barrel above said closure, the other end of said swinging member being secured to the top of said closure, a locking member secured to said closure, one side of said closure adapted to be seated in said bracket, the opposite side of said closure adapted to be supported by said locking member.

JOHN JANUCHOWSKY.

In the presence of—

M. C. HAMMON,
H. G. FLETCHER.
